UNITED STATES PATENT OFFICE.

JOHN NELSON, OF CHICAGO, ILLINOIS, ASSIGNOR TO MARQUETTE TOOL & MANUFACTURING COMPANY, OF CHICAGO, ILLINOIS, A CORPORATION OF ILLINOIS.

POWER PRESS.

Application filed November 2, 1922. Serial No. 598,698.

To all whom it may concern:

Be it known that I, JOHN NELSON, a citizen of the United States, and a resident of Chicago, Cook County, and State of Illinois, 5 have invented certain new and useful Improvements in Power Presses, of which the following is declared to be a full, clear, and exact description.

This invention relates to power presses 10 and one of its principal objects is to provide pressure operated balancing means whereby the usual heavy fly wheel may be dispensed with. Another object is to provide pressure operated balancing means for the ram, 15 which will enable the press to be built with a lighter crank shaft than is required for a press of the same capacity and power as one equipped with the balancing means embodying the present invention. Another object 20 is to provide means for storing up energy, (independent of the fly wheel) on the up stroke of the ram. Another object is to provide means for storing up energy on the up stroke of the ram, (independent of 25 the fly wheel), and for delivering said stored up energy to the ram on its down stroke, in lines parallel with the direction of movement of the ram. Another object is to provide means for storing up energy on the 30 up stroke of the ram, (independent of the fly wheel), and for utilizing said stored up energy in conjunction with the usual crank shaft of the press.

This invention has been designed for use 35 in connection with presses which employ draw-ring or blank holding mechanism to apply pressure to the marginal portions of the blank while the press is doing its work, and one of the objects of the present invention is to provide improved means for operating the draw-ring. In certain classes of work it is important that greater pressure be applied to the draw-ring at certain places than at others, and one of the objects of 40 this invention is to provide means for producing additional pressure upon the draw-ring at any one or more various places thereon as is desired.

Other objects and advantages will occur 45 in the course of this specification, and with all of said objects and advantages in view, this invention consists in the several novel features hereinafter fully set forth and more particularly defined in the appended claims.

The invention is clearly illustrated in the 55 accompanying drawings, in which:

Fig. 1 is a side elevation, partly broken out, of a power press embodying a simple form of the present invention, showing the ram at the top of its up stroke; Fig. 1^a is 60 a diagrammatic view of compressed air tanks used in connection with the press; Fig. 2 is a vertical cross section of the press taken on the line 2-2 of Fig. 1, showing the ram at the bottom of the down stroke; 65 Fig. 3 is a view, partly in plan and partly in horizontal section, the line of section being indicated at 3-3 in Fig. 1; Fig. 4 is a view, partly in under plan and partly in horizontal section, the line of section being 70 indicated at 4-4 in Fig. 1; Fig. 5 is a detail, vertical section of certain members of the draw-ring actuating means, the line of section being indicated at 5-5 in Fig. 3; Fig. 6 is a view similar to Fig. 5 but showing the parts in a different position; Fig. 7 is a detail, horizontal section taken on the line 7-7 of Fig. 5; Fig. 8 is a detail, horizontal section taken on the line 8-8 of Fig. 5; Fig. 9 is a vertical longitudinal section 75 through a fragment of a die press illustrating a modified form of draw-ring mechanism.

Referring first to Figs. 1 to 8, inclusive, which illustrate the preferred embodiment 85 of the invention, the reference character 10 designates the base, 11 the bed, 12 the bolster and 13 the upright side frame members of a power press of ordinary and well known construction. Resting upon and secured to 90 the bolster, is the female die 14, and cooperating therewith is the punch or male die 15, which is secured to the ram 16 by bolts as is well understood. The ram 16 is guided upon the side frame members 13 to move 95 lengthwise thereof. Connecting rods 17 connect the ram 16 with the cranks 18 of the crank shaft 19, as is well understood, and the crank shaft is journaled in bearing boxes 20 formed in the upper ends of the side frame 100 members 13. A back geared press is illustrated in the drawings, and as shown, the crank shaft 19, is driven from a main drive shaft 21, by a pinion 22 on the main drive shaft 21, and a gear wheel 23 on the crank shaft, which gear wheel meshes with said pinion. Clutch mechanism (not shown) 105 may be provided, as is customary for start-

ing and stopping the press. The upper ends of the side frame members 13 are connected by an arch bar 24, bolted or otherwise secured to said side frame members. 5 It is observed that the crank shaft is made considerably lighter than the usual crank shaft employed in presses of this type, and this is because much of the strain thereon is absorbed by the pressure operated balancing 10 means employed in connection therewith. It is also to be observed that the usual heavy fly wheel or balance wheel is dispensed with. Otherwise, the general construction of the press proper is practically similar to that 15 of the ordinary and well known die presses.

Secured to the arch bar 24 is a cylinder 25, closed at the top by a cylinder head 26 and open at the bottom. In said cylinder 25 is a piston 27, which is connected to the ram 16 by piston rods 28, there being at 20 least one piston rod on each side of the crank shaft, extending through lugs 29 formed upon an upwardly extending rib portion 30 of the ram. Lock nuts 31 threaded on the lower ends of said piston rods 28, on the opposite sides of the said lugs 29, rigidly connect the piston rods 28 with the ram. On the up stroke of the ram, the piston 27 compresses the air in the cylinder 25, and on the down stroke of the piston, the compressed air acts in conjunction with the crank shaft in forcing the piston down during its working stroke. It will also 30 be observed that the power derived from the compressed air is exerted through the piston rods 28, in lines parallel with the direction of movement of the ram.

It is preferred to maintain a constant supply of compressed air in the cylinder 25 40 to act on the piston 27, and a compressed air reservoir 32 may be provided which communicates with the interior of the cylinder 25 through a compressed air pipe 33. A suitable air pump (not shown) may be provided for maintaining a pre-determined air pressure in the reservoir 32 and cylinder 25. Obviously, any desired degree of pressure may be had in the reservoir and cylinder 25, with this arrangement, so that a 45 practically uniform pressure may be had upon the piston 27 at all times. Moreover, with the use of the air pressure, as an aid to the crank shaft, less power need be employed for driving said crank shaft, and because of the application of the power from the cylinder to the ram on lines parallel with the movement of the ram, the crank shaft 50 may be made of lighter construction than usual in presses of this kind.

60 The invention has been shown in connection with a press employed in drawing metal and as is customary, a draw-ring 34 is employed, which draw-ring conforms generally to the shape of the die 14, and said draw-ring is bolted or otherwise secured to

a draw-ring plate 35. The draw-ring 34 and draw-ring plate 35 have openings 34^a therethrough, for the punch on die 15. The draw-ring plate 35 is carried by a plurality of stems or rods 36, which have reduced portions 36^a that extend through the draw-ring plate 35, and are secured thereto by nuts 36^b, threaded on the ends of the reduced portions 36^a. The draw-ring plate is thereby securely fastened 75 between the nuts 36^b and the shouldered portions formed between the main parts of the stems 36 and their reduced portions 36^a. The upper ends of the stems or rods 36 pass through openings 37 formed in the ram 16 and have pistons or plungers 38 secured upon their upper ends. When in the position seen in Fig. 1, the pistons or plungers 38 rest upon the upper face of the ram 16 and support the draw-ring plate and draw-ring above the die 14 through the instrumentality of the stems or rods 36.

The pistons 38 are contained in cylinders 39, bolted or otherwise secured to the ram 36, and located in each cylinder, above the piston 38 is a stationarily supported circular or disk like block 40, that forms the upper head of the cylinder 39. Said stationary heads 40 are supported by, and rigidly fastened to head supporting members 41 which are shown in the form of tubular members that are rigidly connected with the arch bar 24 and project down therefrom. As shown, the upper ends of the tubular members are reduced to provide shoulders that bear against the under sides of the arch bar, and threaded on the upper ends of said tubular members are nuts 42, that bear against the upper side of the arch bar. A regulatable and substantially constant supply of compressed air is maintained in the cylinders 39 between the heads 40 and pistons 38 and for this purpose an air reservoir 43 is provided which communicates with a pipe 43^a and branches 43^b that lead into the upper ends of said tubular head supporting members 41. It will be observed that by reason of the air pressure on the tops of the pistons 38, the draw-ring, when it is lowered into contact with the work, is held in pressing contact therewith, which pressure is maintained substantially constant during the time that the punch or die 15 is performing its work.

In the work of drawing certain shapes, 120 it is sometimes necessary to place greater pressure upon certain parts of the marginal portions of the blank than upon others so as to prevent those portions of the blank from being drawn down out of shape, and improved means have been provided for applying additional pressure at a plurality of places upon the draw-ring. In the form illustrated in the drawings, a number of hydraulic or liquid pressure devices are em- 125

ployed between the draw-ring plate and ram, which act to increase the pressure upon the draw-ring at the places where said pressure devices are employed. As illustrated, a number of pressure cylinders 44 are employed, which are disposed about on the ram and bolted or otherwise secured thereto. In said cylinders 44 are pistons 45 which are secured upon the upper ends 5 of stems or rods 46 which extend down through openings 47^a in the ram 16, and are provided upon their lower ends with reduced portions 46^b which extend through the draw-ring plate 35 and have nuts 46^b 10 threaded upon their lower threaded ends. The cylinders 44 contain water, oil or other liquid above the pistons 45, and regulatable means are provided for affording restricted or unrestricted discharge passages from the 15 cylinders 44 whereby when pressure is applied to the liquid contents of the cylinders containing the restricted discharge passages, said contents may escape comparatively slowly, and at a pre-determined flow so as 20 to maintain a substantially constant pressure against the pistons 45, there being means for permitting the liquid to freely reenter the cylinders upon the outward strokes of the pistons. In the embodiment 25 of the invention illustrated, each cylinder 44 has a partition or a head 46 at its upper end, in which is one or more ports 47 through which the liquid contents may pass in either direction. These ports are shown 30 in arcuate form in Fig. 7. Below each head or partition 46 is a valve member, here shown in the form of a disk 48, (see Fig. 8) which also is provided with arcuate ports 49, which in one position may coincide with 35 the ports of the head or partition 46, to obtain a discharge port of maximum area, but by turning the valve disk 48, the solid portions thereof may be caused to overlap the ports 47 of the head 46 so as to decrease 40 the area of said ports 47 to any degree desired, thereby decreasing the size of the discharge orifice or orifices from the cylinder 44, and determining the amount of pressure on the piston in the cylinder. As 45 shown, each valve disk 48 is mounted upon a valve stem 50 which extends up through a central orifice in the head 46 and is connected to a hand lever 51 by means of which the valve disk 48 may be turned to regulate 50 the area of the discharge orifices. Upon the upper end of the valve stem 50 is secured 55 a sleeve 52 by a pin or otherwise, and a stem 53, secured to the hand lever 51, enters said sleeve 52 and has a sliding connection therewith, but is non-rotatively connected thereto, as for instance, by a pin 54 that is secured in the stem 53 and enters vertical slots in the sleeve 52. The valve disk 48 normally seats 60 against the lower face of the head 46 and it is held in seating engagement therewith by a coiled compression spring 56 which is interposed between the upper face of the head 46 and the lower end of the sleeve 52. The upper end of the stem 53 is mounted in a bearing 57 supported by arms 65 70 58 that extend from the wall 59 of a chamber above the cylinder 44 into which the liquid is forced by the action of the piston 45, and said wall 59 may, if desired, be a continuation of the wall of the cylinder 75 44. For holding the head lever 51 at any pre-determined position, a tooth segmental rack 60 may be provided upon the upper end of the annular wall 59 with which engages a tooth 61 on the hand lever. 80

In the operation of the power press above described, a metal blank indicated at A in Fig. 2 is placed upon the lower die 14, while the ram 16 is at the top of its up stroke. The draw-ring 34 is now suspended from the 85 ram, and the pistons 38 that carry the draw-ring plate, are under pressure in the cylinders 39. As the crank shaft 19 is revolved, the ram 16 is moved downward, carrying before it the draw-ring 34, and the air pressure 90 upon the piston 27 in the cylinder 25 cooperates with the crank shaft, to apply force to the punch or die 15 during the working stroke of the press. Before the punch engages the blank, the draw-ring has come into 95 contact with the marginal portions thereof, as seen in Fig. 2, and is thereupon held in pressing engagement with the blank by the action of the compressed air in the cylinders 39 on the tops of the pistons 38. As the ram 16 continues its downward working stroke, the cylinders 39 move down with the ram, but the space between the piston 38 and stationary head 40 in each cylinder 39 remains 100 constant, and each piston 38 is thereby held under pressure in its cylinder 39, and this force is transmitted to the draw-ring through the stems 36 and draw-ring plate 35, and the marginal edge portion of the work is thereby 105 held under pressure between the lower die 14 and draw-ring 34. The pressure on the draw-ring remains substantially constant during the entire interval of time that the punch or die 15 is performing its work on 110 the blank. 115

During the up stroke of the ram, the punch or die 15 is raised, and as soon as the ram engages the lower faces of the pistons 38, it lifts said pistons, and therewith the draw-ring plate, and draw-ring, thereby raising it above the lower die 14. 120

When the auxiliary or hydraulic pressure devices are used, or when one or more of them is used for exerting greater pressure upon the blank at certain places thereon, the valve disk 48 of each working cylinder 44, which is to be used, is set to regulate the area of the discharge orifices of that cylinder. During the first portion of the down stroke 125 of the ram, the pistons 45 in all of the cylinders 130

ders 44 travel down with the ram, and cylinders, but as soon as the draw-ring encounters the blank, the movement of the pistons 45 is arrested although the cylinders 44 continue 5 their downward movement during the remainder of the down stroke. The result is that the liquid in the working cylinders 44 is displaced slowly through the restricted ports therein, and pressure is thereby put upon the 10 tops of the pistons 45 of said working cylinders, whereby additional pressure is produced upon the blank under said working cylinders. Those portions of the blank are thereby held more firmly between the draw-ring and lower die than other portions of the blank. This pressure upon the blank is maintained constantly until the ram reaches the lower end of its down stroke and on the up stroke of the ram the cylinders 44 are 15 lifted with the ram, thereby increasing the distance between the pistons 45 and heads 46, whereupon the valve disks 48 are unseated, permitting the liquid to rapidly reenter the interiors of the pistons 44. It is to be understood 20 that the chambers above the pistons 44 should be of sufficient capacity to contain all of the liquid which is displaced in the associated cylinder 44.

In the modified form of the invention illustrated in Fig. 9, in place of using a fluid for placing pressure upon the draw-ring 34, spring pressure is utilized. In this form of the invention, shouldered rods 36^x are disposed about the dies and extend through the ram 16, draw-ring 34 and bolster 12. The rods 36^x have heads or shouldered portions 36^y at their upper ends which rest upon the ram, and shouldered portions 36^z therebelow which are adapted to engage with the upper face of the draw-ring 34. The rods also have shouldered portions 36^z below the draw-ring, which are adapted to engage with the lower side thereof. This arrangement provides means whereby the rods 36^x have a 45 limited amount of play with respect to the draw-ring and with respect to the ram. Spring pressure is applied to the draw-ring by coiled compression spring 36^s confined under pressure between some member of the press, as for instance, the bolster, and a cross bar 36^v which is held upon the rods 36^x by nuts 36^w, threaded on the lower ends of the rods 36^x.

In the operation of this form of the invention, the draw-ring is held up above the lower die 14 by the shoulders 36^z of the rods 36^x, the rods being normally held upward against the action of the springs 36^s by the engagement of the ram 16 with the heads 36^y of the rods. As the ram descends, the coiled compression springs force the rods 36^x downward, thereby lowering the draw-ring upon the work, and as the ram continues to descend, it leaves the heads 36^y, thereby permitting the coiled compression

springs to draw the shoulders 36^z of the rods against the upper side of the draw-ring, thereby placing pressure upon the blank held between the draw-ring and the lower die. During the up stroke of the ram, 70 the draw-ring is held down until the ram engages the heads 36^y of the rods 36^x and lifts the latter and therewith the draw-ring.

While the invention has been illustrated in connection with a die press for drawing 75 metal, it is not the intention of the inventor to limit the invention thereto, as it is applicable to various types of power presses.

From the above it is to be observed that the compressed air cylinder at the top of 80 the press aids the crank shaft in its work and relieves it of the usual strain occasioned during its working stroke. Furthermore, that when the draw-ring has been brought into pressing engagement with the work, 85 the pressure on the work remains constant through the entire working stroke of the press. Furthermore, that abnormal pressure may be obtained upon the work at any place or places around its marginal portion 90 and that the degree of pressure may be regulated to suit the requirements.

More or less variation of the exact details of construction is possible without departing from the spirit of this invention; 95 I desire, therefore, not to limit myself to the exact form of the construction shown and described, but intend, in the following claims, to point out all of the invention disclosed herein.

I claim as new and desire to secure as Letters Patent:

1. In a power press, in combination with its ram, of a draw-ring, movable with said ram into engagement with the work, a plurality of hydraulic pressure devices connected to said draw-ring and means for regulating the pressure in each pressure device.

2. In a power press, in combination with 110 its ram, of a draw-ring movable with said ram into engagement with the work, compressed air cylinders mounted on said ram and pistons in said cylinders connected with the draw-ring, non-compressible fluid pressure cylinders mounted on said ram having restricted discharge orifices leading therefrom, and pistons in said cylinders connected with the draw-ring.

3. In a power press, in combination with 120 its ram, of a draw-ring, movable with said ram into engagement with the work, compressed air cylinders mounted on said ram and pistons in said cylinders connected with the draw-ring, non-compressible fluid pressure cylinders mounted on said ram having regulatable restricted discharge orifices leading therefrom, and pistons in said cylinders connected with the draw-ring.

4. In a power press, in combination with 130

its ram, of a draw-ring, movable with said ram into engagement with the work, hydraulic cylinders mounted on said ram, said cylinders having regulatable restricted discharge orifices leading therefrom, and pistons in said cylinders connected to said draw-ring.

5. In a power press, in combination with its ram, of a work holder movable with said ram into engagement with the work, a plurality of hydraulic pressure devices connected to said work holder and means for regulating the pressure in each pressure device.

6. In a power press, in combination with its ram, of a work holder movable with said ram into engagement with the work, compressed air cylinders mounted on said ram and pistons in said cylinders connected with the work holder, non-compressible fluid pressure cylinders mounted on said ram having restricted discharge orifices leading therefrom, and pistons in said cylinders connected with the work holder.

7. In a power press, in combination with its ram, of a draw ring movable with the ram into engagement with the work, a plurality of fluid pressure devices connected to the draw ring, and means for regulating the pressure in each of the fluid pressure devices.

30 8. In a power press, in combination with

its ram, of a draw ring movable with the ram into engagement with the work, a plurality of fluid pressure devices connected to the draw ring, and means for regulating the pressure in each of the fluid pressure devices independently, one with respect to the other.

9. In a power press, in combination with its ram, of a draw ring movable with the ram into engagement with the work, a plurality of fluid pressure devices connected to the draw ring, and means for regulating the pressure in each of the fluid pressure devices independently, one with respect to the other, and at will.

40 10. In a power press, in combination with its ram, of a draw ring movable with the ram into engagement with the work, a plurality of fluid pressure devices connected to the draw ring, and means for regulating the pressure in each of the fluid pressure devices.

45 11. In a power press, the combination with its ram, of draw-ring associated with said ram and movable therewith into engagement with the work, fluid pressure cylinders mounted upon the ram, pistons, one in each cylinder connected with the draw-ring, and a compressed air reservoir communicating with said cylinder.

JOHN NELSON.
